UNITED STATES PATENT OFFICE.

BENJAMIN LEV, OF CLEVELAND, OHIO, ASSIGNOR TO THE ECLIPSE RAILWAY SUPPLY COMPANY, OF CLEVELAND, OHIO, A CORPORATION.

LIFE-GUARD.

No. 911,053.

Specification of Letters Patent.

Patented Feb. 2, 1909.

Application filed July 22, 1907. Serial No. 385,029.

To all whom it may concern:

Be it known that I, BENJAMIN LEV, a citizen of the United States, residing at Cleveland, in the county of Cuyahoga and State of Ohio, have invented certain new and useful Improvements in Life-Guards, and do declare that the following is a full, clear, and exact description of the invention, which will enable others skilled in the art to 10 which it appertains to make and use the same.

My invention relates to life-guards for motor cars, and the invention consists in a guard which is designed to come entirely beneath the body of the car and to have engagement with the truck of the car where the guard proper is located, all substantially as shown and described and particularly pointed out in the claims.

In the accompanying drawings, Figure 1 is a side elevation of a car, showing the platform or bottom of the car body, the front portion of the car truck on which the guard is operatively located and the connections between these parts as will hereinafter more fully appear. Fig. 2 is a plan view of the guard mechanism and the immediate parts to which it is attached, omitting the platform shown in Fig. 1. Fig. 3 is a front elevation of the striker mechanism, with obstructing parts sectioned away. Fig. 4 is a view corresponding substantially to Fig. 1 excepting that in this instance the guard is down, presumably as when it strikes a human body, as also will hereinafter more fully appear. Fig. 5 is a plan view corresponding substantially to Fig. 2 but showing the car on a curve and the parts in the relation they sustain to the track and to each other when 40 a curve is turned.

The invention as thus shown is especially adapted to pick up and carry prostrate bodies, such a body being shown at B in Fig. 4. It is furthermore adapted to be located 45 wholly beneath the car body or platform, and in this respect conforms with the requirements of the law in at least some of the States of the United States of America and can be adopted in all cases where, for any 50 reason, it is found desirable to deal with a body that is lying upon the ground rather than with one standing in front of the car. It is practicable, however, to associate with this particular guard another adapted to 55 come at the front of the car and pick up per-

sons who may be struck standing on the track. To these several ends C represents the car or car body or platform, and T the truck. My new and improved safety device intervenes these parts respectively, as shown 60 and comprises what may be termed a striker or striking member S, and guard G, having a series of independently supported and forwardly projecting guard or carrying arms 2, respectively, hinged on cross bar 3 at the 65 rear of said guard. The said arms 2 are so hinged upon cross bar 3 that they will not drop below a level common to all of them, but may be independently raised vertically, and hence when the said guard is bodily 70 lifted to normal position relatively as seen in Fig. 1, the said arms or fingers 2 will occupy a substantially horizontal relation. They are of suitable heavy spring steel with under-turned extremities 4 upon which they are 75 adapted to run upon the surface of the street when down, and comparatively few of these arms are sufficient to intercept and protect a body beneath which they may project, as appears probable in full lines of said 80 arms, Fig. 4, while one or more of said arms may run over or upon said body as indicated in dotted lines in said figure. Hence the importance of having these arms independent of each other and each adapted to act 85 according to the conditions it may meet and leaving the others free to act in like manner with the probability that a prostrate body will be intercepted by at least enough of these arms beneath the same to pick it up 90 and carry it along so as to prevent being run over by the truck. In fact, repeated tests with dummies representing human bodies in form and weight as nearly as possible, and throwing said dummies into every conceivable position, have shown that in no instance did the same escape the guard, but was caught up by it and carried along until the car was stopped, and such tests have been made at every rate of running speed in order 100 to determine the effectiveness of the guard in all probable contingencies, or such as are ordinarily met with in every day car service. Now, the said guard is designed to be dropped by its own gravity into acting position the instant the safety or tripping mechanism strikes a body, and said safety or tripping mechanism comprises the striker or member S, which preferably is a cushioned 105 or yielding part, say of rubber, and is sus- 110

pended in front of the car by hangers 6 and 7 and cross bar 8, or its equivalent. Said hangers are pivotally suspended from suitable brackets 11 rigid on frame or platform 5 C, their normal position being down, as in Fig. 1, which brings striker S to a plane so near the surface of the track that no object that has life, such as a child or a dog, can pass beneath the same if it be lying upon the 10 track.

One of the intermediate hangers 7 has an open notch or recess in its front edge which is engaged by a laterally extending arm 9 rigid with the shaft of drum 10, and the said recess 15 is such that when said hanger swings to the rearward a slight distance under pressure on the striker the said arm 9 is released from said recess or notch and guard G at the rear is dropped down into protecting or picking 20 up position. The mechanism through which this transfer of action is accomplished will presently be described, but attention is now called to drum 10 upon which rope or cable 19 is wound and has its upper looped end in 25 position on the top of the car platform convenient to the motorman to be drawn up and thus wind up said drum and carry all the operating parts of the safety arrangement back to normal or waiting position. To these 30 ends the said drum is supported upon a short shaft 12 rotatable therewith, and arm 9 is rigid with said drum and adapted to drop down when released, as in Fig. 4, from horizontal or locking position as in Fig. 1. In 35 order that said drum and its connections shall positively act when arm 9 is liberated from the hanger even though the joints or parts be somewhat rusted and sticky and not inclined otherwise to respond as they should, 40 I provide a finger 14 immediately over the arm supporting recess in hanger 7 which has the effect of starting the said arm downward when the said hanger is thrown to the rear, the edge of said finger being inclined down- 45 wardly for this purpose, but not interfering with the prompt action of the parts. On the contrary it serves to instantly start rotation toward safety position and promotes the action of parts in any case.

50 Now, the connections to the rear to operate the life guard proper indicated by G, comprise a rod or bar E connected by knuckle or universal joint 15 with drum shaft 12, and a corresponding rod or bar G' slidably 55 mounted at one end on bar E and united by knuckle joint 16 with short shaft member 17 supported in bracket 18 from truck T and somewhat forward thereof to make operating room. The said shaft 17 carries a lateral 60 arm 20 which is engaged by a rigid but more or less curved arm 22 extending upward from the cross bar 3 of guard G' over arm 20 and adapted to bear upon said arm 20 at all times, and which, in this instance, is provided with 65 a bearing roller 23 for the arm 22. In a

sense, the two arms 9 and 20, respectively, one at the front and the other at the rear of the operating parts, stand laterally or horizontally in substantially the same plane and are designed to work or drop by rotation at 70 the same time, the releasing of arm 9 causing the dropping of arm 20 through the connections E and G' and the associate parts at their ends as shown. It will be understood that while these extensible connections 75 lengthwise of bars E and G' are rigid for all purposes of free and mutual rotation to drop the guard fingers 2 the instant they are released, they are flexible for all other purposes, and the two parts E and G' are adapted to slide one upon the other at their ends, which are looped and provided with intervening rollers 24 to promote easy action. The service and value of this extensible or 80 slidable relationship between connecting 85 parts E and G' is particularly apparent in Fig. 5 when a turn or curve of the car is to be made and the forwardly projecting portion of the car body is so far in advance and at one side of the line of travel of the truck that 90 there must be extensibility in these couplings or they could not operate, but no release of mechanism is affected by the curves or turns of the track, and the entire mechanism is designed to remain set relatively as seen in Fig. 95 1 with something of a trigger like engagement particularly between hanger 7 and arm 9, so that the instant that the striker encounters an object that moves it the entire mechanism will be released and the life guard will drop 100 into picking up position before the prostrate body is reached, at whatever speed the car may be going. Of course, if more rapid descent of said arms 2 were needed than gravity gives it could be supplied by means of 105 springs or the like, but said arms are numerous and heavy and have but a short distance to fall before they strike the track and the car will not traverse the distance between the 110 points of the fingers and striker S before the 115 fingers are upon the track. Now, assuming that the parts have been down for action, the motorman has simply to pull upward on cord or cable 19 and rotate the drum, unwinding the cord and in doing this finger 9 will naturally drop into or be engaged in recess 27 and the guard arms at the rear will be raised and everything will be set and in readiness for further contingencies.

In a mechanical sense the connection 120 formed by bars E and G' is a single or unitary connection as such, and telescoping tubes or the like could be substituted. In fact various equivalents are obvious for this and other parts of the mechanism and are 125 understood to be within the invention. Arm 30 strikes bracket 17 when the guard is down, as in Fig. 4.

What I claim is:—

1. In life-guards for cars, a series of inde- 130

- pendently mounted guard arms, in combination with a pivotally suspended striker in advance of said arms, and a rotatable extensible connection operatively engaged with said arms and adapted to be released to drop the arms by the swinging of said striker on its pivots.
2. In life-guards for cars, a series of separately pivoted guide-arms and means adapted to drop said arms to serving position comprising a striker pivotally mounted from the car body before said arms and supporting mechanism for said arms adapted to be released when said striker is operated and comprising an axially rotatable extensible connection.
3. In life-guards for cars, a striking member transversely of the car adapted to swing rearward when struck, a series of guard arms behind said striking member and a rotatable support therefor, and an arm rigid with said support in tripping relation with said striking member, whereby when said member acts said fingers will be released and drop.
4. In life-guards for cars, a suspended striker, in combination with a life-guard, a rotatable mechanism operatively engaged by said striker and means between said guard and said rotatable mechanism adapted to hold said guard in suspended position.
5. In life-guards for cars, a life-guard and a striker in front thereof and means for holding the guard off the ground operatively connected with said striker and comprising parts slidably engaged with each other and rotatable members at the ends of said parts, and a lateral arm on one of said rotatable members adapted to carry said life guard.
6. In life-guards for cars, a striker and hangers suspending the same, in combination with means to carry the said striker having an arm engaged in one of said hangers and a member over the said arm adapted to depress the arm when the hanger is swung away and the arm released.
7. In life-guards for cars, a guard and a striker in front thereof, in combination with a rotatable connection between said parts having a lateral arm at each end, a support for the guard engaged on the rear of said arms and a hanger for the striker engaged by the front arm.
8. In life-guards for cars, a striker mounted on the car body, in combination with a life-guard constructed to be lowered and means to normally hold said guard in elevated position having operative connection with said striker, and means providing a compulsory initial movement of said operative means when the striker is engaged and 60 actuated.
9. A life-guard for cars comprising a transversely arranged striker, a pivotally mounted guard behind said striker adapted to drop to the car track, and extensible releasing connections for said guard operatively engaged with said striker.
10. In life-guards for cars, a pivotally suspended striker, in combination with a pivotally supported guard, devices to carry 70 the guard in raised position and to drop the same when the striker is actuated comprising an extensible shaft and a shaft member supported in fixed bearings and coupled to said extensible shaft and operating connections between said fixed shaft and the guard.
11. In life-guards for cars, actuating mechanism for a guard comprising a striker and a rotatable drum operatively supporting the guard comprising a rotatable drum connected therewith, and a cable on said drum to rotate the same to engage the striker.
12. In life-guards for cars, a life-guard and means to hold the same in suspended position, in combination with a striker and means connecting the same with the life-guard and adapted to drop the guard when the striker is operated, said means comprising a carrying member for the guard, and an extensible connection between said carrying member and the striker having initial operating connection with the striker and coupled with said carrying member.
13. A car truck and a life-guard pivotally mounted on the front thereof, in combination with a car body and a striker pivotally supported at the front thereof, and an extensible operating connection between said striker and said life-guard constructed to drop the guard when the striker is operated, whereby the life-guard is held in an operating position at different angles in respect to the striker and accommodation is made for turning curves in tracks, substantially as described.
- In testimony whereof I sign this specification in the presence of two witnesses.
